HAND LAMP FOR ATTACHMENT TO
BATTERIESArthur P. Sauer, Fairfield, Conn., assignor to The
Kilborn-Sauer Company, Fairfield, Conn., a
corporation of Connecticut

Application October 29, 1948, Serial No. 57,350

6 Claims. (Cl. 240—10.61)

1

The present invention relates to a hand lamp for attachment to a battery, particularly of the type for producing a high-powered beam, and wherein the battery employed is of relatively large size, containing for instance 20 cells and having a rating of 7½ volts. Such batteries are commercially produced in various forms, the battery best suited for the purpose of the present invention being a battery of generally rectangular form having outwardly projecting flanges at its upper and lower edges, and having at its upper side a pair of binding posts for attaching the lead wires from the lamp.

An object of the invention is to provide a lamp having a supporting bracket structure adapted to be mounted directly upon the upper side of the battery and to be clampingly engaged with the edge flange thereof to thereby support the battery from the bracket, so that the lamp and the battery become a rigidly connected portable unit. A further object is to provide a bracket having clamping arms adapted to clamp the flanges at two opposed sides of the battery as well as the flange at one end, thereby effectually preventing accidental disengagement or slippage of the battery with respect to the bracket.

Another object is to provide a carrying handle formed upon the bracket and so disposed that when the battery is connected to the bracket the center of gravity of the assembled lamp and battery will be directly beneath the handle thereby distributing the weight so that it can be easily carried. Heretofore lamps of this type have had a carrying handle provided directly upon the lamp casing so that the strain of the weight of the battery was imposed upon the connection between the lamp and the bracket, and where it was desired to dispose the lamp in a tilted position, to direct its beam upwardly or downwardly while it was being carried, this arrangement tended to cause the lamp to resume its normal position due to the weight of the battery. The arrangement of the handle directly upon the bracket enables the lamp to be positioned as desired entirely independently of the weight of the battery. It is further proposed to provide a handle so arranged that the lamp and battery may be tilted upwardly or downwardly to direct the light beam by a simple wrist movement of the hand gripping the handle.

With the above and other objects in view, an embodiment of the invention is shown in the accompanying drawings, and this embodiment will be hereinafter more fully described with reference thereto, and the invention will be finally pointed out in the claims.

2

In the drawings:

Fig. 1 is a side elevation showing a lamp attached to the battery, according to the invention.

Fig. 2 is a front elevation.

Fig. 3 is a top plan view.

Fig. 4 is a rear elevation of the lamp partially broken away and removed from the battery.

Similar reference characters indicate corresponding parts throughout the several figures of the drawings.

Referring to the drawings the lamp, according to the illustrated exemplary embodiment of the invention, comprises a conventional type of lamp unit including a casing 10 in which the usual lamp bulb, reflector, and lens are mounted, these preferably being in the form of a sealed beam reflector type lamp unit. The casing is provided at its lower side with a downwardly projecting apertured lug member 11, rigidly connected thereto, as by a threaded stud portion 12 engaged upwardly through an apertured bearing portion 13 of the casing and secured by an interiorly disposed nut 14.

25 The apertured lug member is pivotally engaged in a slotted post member 15 provided with a transversely disposed bolt 16 engaged through the apertured lug member and forming a tilting support for the lamp casing, tightening of the bolt adapted through binding action of the two sides of the post member to fix the tilted position of the lamp. The post member is secured to the forward end of the bracket 17 by means of a downwardly extending threaded stud 18, engaged through a hole 19 in the forward end of the bracket, and secured by a washer 20 and nuts 21 engaged upon the stud at the underside of the bracket. This means of attachment permits rotational adjustment of the post for the purpose of directing the beam in any desired direction with respect to the bracket.

The bracket is of generally T-shape in plan outline to provide three arms for clamping engagement with the battery 22, the latter being provided at its upper and lower edges with outwardly projecting peripheral flanges 23 and 24, and being provided at its upper side with binding posts 25 and 26. The forwardly projecting arm 20 of the bracket is provided at its underside at a point rearwardly of the supporting post 15 of the lamp with a hook-shaped flange 27 adapted to engage about the forward end of the flange 23 of the battery as clearly shown in Fig. 1. The other two arms extend transversely over the two side portions of the flange 23, one arm being pro-

vided with a hook-shaped flange 28 at its outer end adapted to engage about one side portion of the flange 23. The other arm is provided at its outer end with a downwardly extending bearing portion 29 having a threaded hole 30 engaged by a set screw 31, on the inner end of which is swivelly connected a rectangular clamping plate 32 adapted to clamp against the side of the battery beneath the flange 23, as shown clearly in Fig. 2, to thus secure the battery to the bracket. With the screw 31 screwed outwardly, as shown in Fig. 4 the plate 32 is drawn against the inner side of the bearing portion 29, and in this position the bracket may be engaged with the battery simply by hooking the flange 28 with the flange 23 at one side, the plate 32 clearing the flange 23 at the other side. Thereupon the forward hook flange 27 is slid into engagement with the forward end of the flange 23, and the screw 31 is turned inwardly to bring the plate 32 into binding and locking position beneath the flange 23. A recess 33 is provided in one edge of the forwardly extending arm of the bracket to provide a clearance space for the binding post 25 of the battery.

Integrally formed upon the bracket is an upwardly extending hollow handle supporting arm 34 provided at its upper end with an integrally-formed rearwardly-extending horizontally-disposed handle extension 35, preferably having a rubber hand-grip sleeve member 36 engaged thereon. The arrangement of the handle is such with respect to the center of gravity of the assembled lamp and battery that the latter is suspended beneath the handle in a substantially horizontal carrying position. By a slight upward or downward movement of the wrist, the beam of the lamp can be directed upwardly or downwardly as desired with very little muscular effort. When it is desired to maintain the beam of the light either upwardly or downwardly, the angular position of the lamp may be adjusted as desired by tilting about the axis of the bolt 16, the adjusted position being fixed by tightening the bolt.

The hollow handle supporting arm 34 is provided in its forward wall near its upper end with an aperture 37 in which a toggle switch unit 38 is secured, this switch unit having the usual internal part to which the lead wires are attached and an external toggle lever, the latter being conveniently placed so that it may be operated by the thumb of the hand engaged about the handle. One conductor wire 39 from the lamp extends through an aperture 40 in the forward wall of the arm 34, and is connected to one side of the switch 38, the other side of the switch having a conductor wire 41 connected thereto and extended outwardly through an aperture 42 in the side wall of the arm 34, being provided at its end with a connector ring 43 for connection to the binding post 26. The other conductor wire 44 from the lamp is provided at its end with a connector ring 45 which is connected to the binding post 25 of the battery.

I have illustrated and described a preferred and satisfactory embodiment of the invention, but it will be understood that changes may be made therein within the spirit and scope thereof as defined in the appended claims.

What is claimed is:

1. In a hand lamp for attachment to a battery, wherein the battery includes a casing having a rectangular peripheral flange at its upper end, a bracket member adapted to span the upper side of said battery, transversely arranged clamping

means carried by said bracket at opposed sides for engagement with the underside of said flange at opposed sides of said battery, longitudinally arranged clamping means carried by said bracket for engagement with the underside of said flange at the forward end of said battery, a lamp unit connected to said bracket, and a handle connected to said bracket and disposed substantially directly above the center of gravity of the connected battery and bracket.

2. In a hand lamp for attachment to a battery, wherein the battery includes a casing having a rectangular peripheral flange at its upper end, a bracket member adapted to span the upper side of said battery, transversely arranged clamping means carried by said bracket at opposed sides for engagement with the underside of said flange at opposed sides of said battery, longitudinally arranged clamping means carried by said bracket for engagement with the underside of said flange at the forward end of said battery, a lamp unit connected to said bracket at its forward end, and a handle connected to said bracket at its rearward end and disposed substantially directly above the center of gravity of the connected battery and bracket.

3. A hand lamp for attachment to a battery, wherein the battery includes a casing having a rectangular peripheral flange at its upper edge, a bracket of substantially T-shape in plan outline including a transverse portion adapted to transversely span the upper side of said battery and having clamping means at its outer ends for engagement with the underside of said flange at opposed sides of said battery, and a forwardly extending arm portion having clamping means adapted for engagement with the underside of said flange at the forward end of said battery, a lamp unit mounted upon the forward end of the arm portion, and a handle member connected to said transverse portion of said bracket and extending upwardly and rearwardly therefrom.

4. A hand lamp for attachment to a battery, wherein the battery includes a casing having a rectangular peripheral flange at its upper edge, a bracket of substantially T-shape in plan outline including a transverse portion adapted to transversely span the upper side of said battery and having clamping means at its outer ends for engagement with the underside of said flange at opposed sides of said battery, and a forwardly extending arm portion having clamping means adapted for engagement with the underside of said flange at the forward end of said battery, a lamp unit mounted upon the forward end of the arm portion forwardly of said clamping means thereof, and a handle member connected to said transverse portion of said bracket and extending upwardly and rearwardly therefrom.

5. A hand lamp for attachment to a battery, wherein the battery includes a casing having a rectangular peripheral flange at its upper edge, a bracket of substantially T-shape in plan outline including a transverse portion adapted to transversely span the upper side of said battery and having clamping means at its outer ends for engagement with the underside of said flange at opposed sides of said battery, and a forwardly extending arm portion having clamping means adapted for engagement with the underside of said flange at the forward end of said battery, a lamp unit mounted upon the forward end of the arm portion, and a handle member integrally formed upon said transverse portion of said

bracket and extending upwardly and rearwardly therefrom.

6. A hand lamp for attachment to a battery, wherein the battery includes a casing having a rectangular peripheral flange at its upper edge and a pair of binding posts at its upper side, a bracket of substantially T-shape in plan outline including a transverse portion adapted to transversely span the upper side of said battery and having clamping means at its outer ends for engagement with the underside of said flange at opposed sides of said battery, and a forwardly extending arm portion having clamping means for engagement with the underside of said flange at the forward end of said battery, a lamp unit mounted upon the forward end of the arm portion, a handle member connected to said transverse portion of said bracket and extending upwardly and rearwardly therefrom, a switch carried by said handle portion, a conductor wire connected between said lamp unit and said

switch, a conductor wire connected to said switch and adapted to be connected to one of said binding posts, and a conductor wire connected to said lamp and adapted to be connected to the other of said binding posts.
